(Cl. D64—10)

To all whom it may concern:

Be it known that I, John Brenner, a citizen of the United States, residing in Los Angeles, in the county of Los Angeles and State of California, have invented a new, original, and ornamental Design for a Portable Name Imprinter, of which the following is a specification, reference being had to the accompanying drawing, forming part thereof.

I claim:

The ornamental design for a portable name imprinter, as shown.

JOHN BRENNER.
